US0D1096392S

(12) United States Design Patent (10) Patent No.: US D1,096,392 S
(45) Date of Patent: * Oct. 7, 2025

(54) ONE-CELL BEVERAGE BOX

- (71) Applicant: Pratt Corrugated Holdings, Inc., Brookhaven, GA (US)
- (72) Inventors: Shifeng Chen, Newport News, VA (US); Greg Sollie, Sharpsburg, GA (US); Jamie Waltermire, Peachtree City, GA (US)
- (73) Assignee: Pratt Corrugated Holdings, Inc., Brookhaven, GA (US)
- () Term: 15 Years

(21) Appl. No.: 29/928,461

(22) Filed: Feb. 12, 2024

Related U.S. Application Data

(57) CLAIM

The ornamental design for a one-cell beverage box, as shown and described.

DESCRIPTION

FIG. 1 is a rear perspective view of a one-cell beverage box showing the claimed design with a top portion positioned in an open configuration and a telescoping portion positioned in a telescoped configuration.

FIG. 2 is a rear elevation view thereof.

FIG. 3 is a front elevation view thereof.

FIG. 4 is a right-side elevation view thereof.

FIG. 5 is a left-side elevation view thereof.

FIG. 6 is a top plan view thereof.

FIG. 7 is a bottom plan view thereof.

FIG. 8 is a plan view of the one-cell beverage box shown in a fully collapsed configuration.

FIG. 9 is a front perspective view of the ONE-cell beverage box shown in a partially collapsed configuration; and, FIG. 10 is a front perspective thereof.

Those features shown in broken lines form no part of the claimed design.

1 Claim, 7 Drawing Sheets
